CLAIM

The ornamental design for a telephone stand or similar keyboard article, substantially as shown and described.

DESCRIPTION

FIG. 1 is a top front perspective of our design for a telephone stand or similar keyboard article;

FIG. 2 is a front elevation thereof;

FIG. 3 is a rear elevation thereof;

FIG. 4 is a side elevation thereof, the opposite side being essentially a mirror image of the side shown; and

FIG. 5 is an end elevation thereof, the opposite end being essentially a mirror image of the end shown.

FIG. 1

FIG. 3

FIG. 2

FIG. 4

FIG. 5
